(57) **CLAIM**

I claim the ornamental design for a tongue scraper with a tablet holder, as shown and described.

DESCRIPTION

FIG. 1 is an upper perspective view of the tongue scraper with a tablet holder showing my design.

FIG. 2 is a side view thereof, an opposite side view being a mirror image thereof;

FIG. 3 is a top plan view thereof;

FIG. 4 is a bottom view thereof;

FIG. 5 is an end view thereof;

FIG. 6 is an opposite end view thereof; and,

FIG. 7 is a side view thereof.

The broken line showing in FIGS. 1 and 7 of the tablet are for illustrative purposes only and forms no part of the claimed design.
